UNITED STATES PATENT OFFICE

JAMES HENRY TOBIN, OF FOND DU LAC, WISCONSIN, ASSIGNOR TO TOBIN TOOL & DIE COMPANY, INC., OF FOND DU LAC, WISCONSIN, A CORPORATION OF WISCONSIN

REFRIGERATOR TRAP

Application filed June 18, 1932. Serial No. 617,942.

The invention relates to refrigerator traps and has for an object the provision of a trap of this type which can be easily installed, readily cleaned and economically manufactured, and which is of such construction as to avoid loss of parts during shipment and installation.

Another object of the invention is to provide a refrigerator trap in which condensation collecting on the exterior of the drainage conduit is discharged into the trap and thus prevented from accumulating in the refrigerator.

The invention further consists in the several features hereinafter set forth and more particularly defined by the annexed claims.

In the accompanying drawing, Fig. 1 is a sectional elevation of a refrigerator trap embodying the invention.

Fig. 2 is a detail view of a drain tube assembly for the trap.

Fig. 3 is a top plan view of a sealing member of the trap, parts being broken away and parts being shown in section, and

Fig. 4 is a sectional view taken along the line 4—4 of Fig. 2.

In the drawing, the numeral 10 designates the bottom wall of a refrigerator having formed therethrough a bore or opening 11. A trap cup 12 within the refrigerator rests on the bottom wall 10 and has a reduced central outlet pipe 13 which removably enters the opening 11. The upper edge of the outlet pipe extends within the cup to form an annular liquid-receiving sealing well 14 with the surrounding walls of the cup. The trap cup is preferably formed of a single sheet metal stamping having reentrant intermediate portions defining the inner walls of the annular sealing well.

The usual ice compartment, not shown, is spaced above the bottom wall of the refrigerator and is provided with a depending drip pipe 15 in vertical alignment with the trap cup 12. A drain tube 16 extends between the drip pipe 15 and the trap cup 12 and at its upper end is loosely telescoped over the drip pipe 15.

The lower end of the drain tube 16 is supported on the flaring outer surface of a bell

shaped sealing hood 17 which has its lower edge surrounding the upper end of the trap cup outlet pipe 13 and extending into the sealing well 14 of the cup. The outer surface of the sealing hood is provided with radially extending ridges 18 on which the lower edge of the drain pipe 16 rests without obstructing drainage. The lower rim portion of the sealing hood carries spaced feet 19 which rest on the bottom wall of the cup. The sealing hood is preferably formed by a single sheet metal stamping.

An annular sheet metal cover 20 is slidably mounted on the drain tube 16 and has a flange 21 resting on the upper edge of the trap cup, and a depending skirt 22 which slidably fits within the trap cup. The cover has a dished portion 23 loosely surrounding the drain tube so that condensation collecting on and flowing down the exterior of the drain tube will drain into the trap cup, thus preventing the condensation from accumulating in the refrigerator. Condensation collecting on the exterior of the drip pipe 15 will drain into the drain tube 16.

In order to avoid loss of the sealing hood 17 and to facilitate installation of the trap, the sealing hood is attached to the lower end of the drain tube 16. In the present instance the sealing hood has an upper cylindrical portion 24 of reduced diameter received in the lower end of the drain tube 16. Vertical extensions of the ridges 18 are formed on the cylindrical portion 24 and frictionally engage the inner surface of the drain tube to firmly retain the sealing hood on the tube, the walls of the drain tube being somewhat resilient to insure the retention of the sealing hood. In assembling the sealing hood onto the drain tube it is only necessary to push the reduced end of the hood into the tube, and when the trap is to be cleaned the sealing hood can be withdrawn from the tube. The sealing hood when in place on the drain tube prevents withdrawal of the cover 20 from the lower end of the tube, and an embossment 25 formed on the upper portion of the drain tube prevents withdrawal of the cover from the upper end of the tube. The drain tube, cover, and sealing hood thus

form a unit assembly, as seen in Fig. 2, avoiding loss of the cover and sealing hood during shipment, and facilitating the installation and removal of the trap, as hereinafter described.

To install the trap, the trap cup 12 is set into place on the bottom wall of the refrigerator and filled with water to the water line. The drain tube assembly is telescoped over 10 the drip pipe 15 and swung into alignment with the trap cup into which the tube is then lowered to bring the sealing hood into operative position within the trap cup, the cover 20 being slid downwardly onto the cup to 15 enclose the liquid space in the cup and to center the hood within the cup. In some instances, the trap cup may be set in place after the drain tube is slipped over the drip pipe.

20 When the trap is to be cleaned it can easily be removed from the refrigerator, the drain tube assembly being lifted bodily from the trap cup and then swung laterally out of alignment with the cup, and the sealing hood being subsequently withdrawn 25 from the tube. After the trap is cleaned it can easily and properly be replaced in the manner above described.

What I claim as new and desire to secure 30 by Letters Patent is:

35

40

45

50

55

60

65

1. In a refrigerator trap, the combination of a trap cup having a liquid space, a drain tube mounted above said trap cup and having resilient walls, and a sealing hood having a lower edge entering said liquid space and an upper portion entering the lower end of said tube and having spaced projections frictionally engaging the inner surface of the resilient walls of said tube to detachably secure said hood to said tube. 70

2. In a drain trap, the combination of a drain tube, and a sealing hood having an upper portion inserted in the lower end of said tube and frictionally engaging the inner walls of said tube to secure together the tube and hood, there being a liquid passage between said hood and the inner walls of said tube. 80

3. A sealing hood for a drain trap, comprising an inverted cup-shaped member having a reduced upper end adapted to be inserted into the lower end of a drain tube and provided with spaced projections frictionally engageable with the inner walls of the tube. 85

In testimony whereof I affix my signature.

JAMES HENRY TOBIN. [L. S.]
